METAL CUTTING TOOL

Evan L. Solomon, Detroit, Mich.

Application June 14, 1938, Serial No. 213,668

3 Claims. (Cl. 30—241)

This invention relates to a metal cutting tool.

An object of the invention is the construction of a metal cutting tool which can be easily manipulated by the operator, with speed, as well as being adaptable to a wide range of metal gauges.

Another object of the invention is the construction of a simple and efficient tool which can be held in the hand and guided easily in the desired direction of the cutting, motor power being supplied to the tool by an air hammer, the upper part of the tool being peculiarly constructed for easily receiving a portion of the air hammer, for operation.

A still further object of the invention is the construction of a barrel or casing upon which is adjustably mounted a novel foot device, and means is furnished for locking the foot device in an adjusted position upon the casing.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Figure 1 is an elevated front view of the tool constructed in accordance with the present invention, while

Figure 2 is a side view of the same.

Figure 3 is a top plan view.

Figure 4 is a sectional view taken on line 4—4, Figure 2, and looking in the direction of the arrows.

Figure 5 is a sectional view taken on line 5—5, Figure 1, and looking in the direction of the arrows.

Figure 6 is a sectional view taken on line 6—6, Figure 5, and looking in the direction of the arrows.

Figure 7 is a sectional view taken on line 7—7, Figure 5, and looking in the direction of the arrows.

Figure 8 is a bottom plan view of the foot device.

Figure 9 is a perspective view of the foot device.

Figure 10 is a sectional view taken on line 10—10, Figure 5, and looking in the direction of the arrows.

Referring to the drawings, in which I have shown the preferred embodiment of my invention, the barrel or casing 1 is provided with an enlarged upper or outer end 2 and a reduced lower or inner end 3; the exterior surface of the

end 3 is screw threaded for the purpose herein-after described.

The upper or outer end 2 is a receiving end for a portion of an air hammer (not shown) which extends into this end and engages the reciprocating piston 4. An annular groove 5 is formed upon end 2, and in this groove is positioned a clamping band 6, which band is provided on its ends with parallel ears 7; in said ears is a bolt 8 provided with nut 9, whereby the tool can be tightened on an air hammer. The end 2 is provided with a plurality of longitudinally extending slots 10 for allowing a slight contraction for more efficiently accomplishing the tightening or affixing of the tool on the air hammer.

The piston 4 extends entirely through casing 1, and is provided on its inner end with a cutting tool 11. In the large chamber 12 of casing 1 I place an annular rubber block 13; this block is against the inner end of chamber 12 (Fig. 5). Against the outer end of annular block 13 is a metal plate or washer 14. Engaging the outer face of washer 14 is an annular compression plate or ring 15; this ring 15 is integral with piston 4, whereby when the air hammer strikes the blow, the impact, acting on the rubber block 13, will cause the cutting tool to rebound after it has completed the cutting action.

The foot device (Fig. 9) comprises an angular broad body 16, which is provided with an inclined side face 17 in which are two screw sockets 18. Extending inwardly from body 16 is an inclined interiorly-threaded sleeve 19. The body 16 is provided with an integral horizontal runner 20, and this runner is provided with an integral curved extension 21. Extension 21 has a rearward, curved guiding shoulder 22. A bottom cutting die 23, dove-tail in shape, is positioned horizontally in the extension 21, and by means of a suitable screw 24 this die is fixedly secured in place. The runner 20 is bevelled on its lower face as shown by dotted line 25, Fig. 5, to facilitate the movement of the tool during the operation thereof. The upper cutting tool 11 has its inner flat face (Fig. 10) registering with the inner edge of die 23 and the inner face of the curved extension 21, as clearly shown, for accomplishing in an excellent manner the cutting function. An annular tool guide 26 (Figs. 1 and 5) comprises an inclined body 27 through which extends bolts 40 or screws 28; these bolts or screws extend at their inner ends into the screw sockets 18 (Fig. 9), whereby the tool guide is securely fastened in place. Extending from the inclined body 27 is a flat arm 29 and this arm terminates at its outer 45 50 55

end in a downwardly and inwardly extending finger 30; this finger 30 normally bears against the flat inner edge of the cutting tool 11, as clearly seen in Figure 10, whereby the cutting tool is kept from turning; it is retained always in the proper cutting position.

As it is obvious that the interiorly-threaded sleeve 19 can be screwed longitudinally of the reduced lower end 3, an adjustment of the foot device is thereby accurately obtained upon casing 1, in the event the cutting tool 11 becomes dull and is consequently shortened by the grinding.

To secure the foot device in an adjusted position upon casing 1, a locking-nut collar 31 is threaded on the lower extension 3 against the inner end of sleeve 19. By screwing collar 31 tightly against screw 19, the foot device is securely locked in its adjusted position. Therefore, I have shown a novel foot device, which is adjustably mounted upon a casing, together with means for locking the foot device in an adjusted position.

The tapering or wedge-shaped structure of the runner 20, emphasized by line 25 in Fig. 5, facilitates forward movement of the tool by slightly pressing downward one edge of the metal being cut; in other words, this novel construction of my tool or foot device facilitates greatly the cutting action of the tool.

On the inner face of body 16 (Fig. 9) is a slightly overhanging segment 32, to provide metal clearance in making a right-hand circular cut.

It is to be noted that the lower or inner end of casing 1 is bored sufficiently to receive the piston 4 without binding. Further, the rubber block 13 efficiently performs the service of absorbing the shock of the downward thrust of the piston, carrying the cutter 11, and rebounds said cutter.

From extensive experience in actual practice, I have found that my tool is not only simple in operation, but is efficient and durable.

While I have described the preferred embodiment of my invention and illustrated the same in the accompanying drawings, certain minor changes or alterations may appear to one skilled 45 in the art to which this invention relates during

the extensive manufacture of the same and I, therefore, reserve the right to make such changes or alterations as shall fairly fall within the scope of the appended claims.

What I claim is:

1. In a metal cutting tool, the combination of a casing provided with a foot device, said foot device provided with a die, a tool guide engaging said foot device, means holding said tool guide on said foot device, said tool guide comprising an inclined body provided with an outwardly extending arm, said arm terminating in a downwardly and inwardly extending finger, an edge of said finger being in alignment with an edge of said die, and said casing provided with cutting means passing in its movement the registering edges of said finger and die.

2. In a metal cutting tool, the combination of a casing, a foot device provided with a sleeve and a runner on said casing, said runner provided with a die, a tool guide on said foot device and provided with a guiding finger between said sleeve and die, and a cutting unit on said casing and guided and retained against rotary movement by said guiding finger.

3. In a metal cutting tool, the combination of a casing, a foot device on said casing, said foot device comprising an angular body terminating at its upper end in a forwardly-extending, internally-threaded, integral sleeve, said angular body provided at its lower end with a horizontal runner, said runner provided with an outwardly-extending curved extension, said extension provided with a detachable die, said extension provided at its rear with a curved guiding shoulder, said angular body provided on its inner face with an overhanging segment, said body provided with an inclined side face and with threaded sockets in said side face, a tool guide against said socketed side face, screws extending through said tool guide and into said threaded sockets, said tool guide provided with a finger extending under the lower end of said sleeve, and cutting means on said casing and cooperating with said die.

EVAN L. SOLOMON. 45
